BRAKE LINING APPLIER

Andrew O. Wisti, Minneapolis, Minn.

Application October 6, 1930. Serial No. 486,693

5 Claims. (Cl. 29—84)

This invention relates to a stretching device, or a device for stretching and fitting a flexible member into tight engagement with the surface of another member. While the invention may have various applications, it particularly is designed for stretching and fitting brake linings to brake shoes. Such structures are now commonly used in brake devices, and one common use of the same is in automobile brakes. It is desirable and important to have the brake lining brought into firm and intimate contact with the brake shoe before it is secured to the shoe. Many brake linings are now of the molded type, and are more or less distorted before being placed on the shoe. It is thus increasingly important to have some device which will stretch and fit the lining or band tightly to the shoe. Bands are also now being supplied in cut lengths just sufficient to fit the length of the shoe, and it is desirable to have some device which will stretch and fit these short lengths to the shoe.

It is an object of this invention, therefore, to provide a device by means of which a brake lining or band can be quickly and easily stretched and pressed into firm engagement with the brake shoe.

It is a further object of the invention to provide a device by means of which the brake lining or band can be stretched longitudinally over the shoe and pressed into very firm engagement with the surface of the shoe.

It is still another object of the invention to provide a device comprising a pair of swinging arms, together with means for engaging the band or lining at the ends of these arms and moving the arms apart while the band is pressed against the shoe to draw and press the band tightly against the shoe.

It is still another object of the invention to provide a device comprising a flexible strip of material such as metal, adapted to engage the band or lining with means for bringing the ends of the strip against the band to press the same against the shoe and then moving the ends of the strip away from each other to progressively and tightly draw the band into close engagement with the shoe.

It is still further an object of the invention to provide a device for drawing and pressing a brake band against a shoe by engaging the band at one point with a flexible strip of material, and then pressing the other end of said strip against the band and moving it away from said point to draw and press the band against the shoe.

It is another object of the invention to provide a device comprising a pair of oppositely extend-

ing arms, a member to which the adjacent ends of said arms are pivoted, a flexible strip of metal connected to and extending between the remote ends of said arms, a screw carrying said member, a block through which said screw extends and into which it is threaded, together with means extending from said block for engaging a brake shoe, whereby when said means is engaged in the shoe and said strip placed against the lining on the shoe, said screw may be rotated to move the ends of said arm and said strip apart to draw and stretch said band into tight engagement with the shoe.

It is more specifically an object of the invention to provide a device for stretching and fitting a brake band or lining to a brake shoe, comprising a block, a screw extending through and threaded into the said block, a member carried by said screw below said block, a pair of arms pivoted to said member at opposite sides thereof and extending in opposite directions therefrom, a flat metal strip secured to and extending between the remote ends of said arms, a pair of members pivoted at either side of said block and having lower hooked ends adapted to engage under the edges of the brake shoe, and a spring for drawing said members together, the upper end of said members being formed as handles or finger pieces for separating said members.

These and other objects and advantages of the invention will be fully set forth in the following description made in connection with the accompanying drawing, in which like reference characters refer to similar parts throughout the several views, and in which:

Fig. 1 is a view in side elevation of the device showing the same in engagement with a brake band disposed on a brake shoe;

Fig. 2 is a horizontal section on line 2—2 of Fig. 1;

Fig. 3 is a vertical section on line 3—3 of Fig. 1, and

Fig. 4 is a view in side elevation of the device, certain parts being shown in dotted lines in a different position;

Referring to the drawing, a device is shown comprising a block 10 through which extends the screw 11 threaded into said block. Said screw 11 has an operating handle or wheel 12 at its upper end. The screw has collars 13 formed at its lower end, between which is disposed the top of a channel plate 14, said screw thus having a reduced portion extending through said plate. Plate 14 has pairs of lugs 14a at its end, disposed respectively at the sides thereof, said lugs being 110

embraced by lugs 15a formed at the ends of arms 15 also shown as in the form of channel members, said arms extending in opposite directions, and the flanges thereof tapering to a small width 5 at their outer ends. Lugs 14a and 15a are pivotally connected by headed rivets 16. As shown in Figs. 1 and 4, arms 15 are curved, the concave side thereof being downward. A flat and flexible strip of metal 17 extends between the ends of arms 10 15, the same being shown as overlapping the outer end portions of said arms and being secured thereto by headed screws 18. Block 10 is bifurcated at its ends and embraces at each end a member 15 of flat formation, said members 19 extending downwardly from block 10 and having hook portions 19a at their lower ends. The upper ends of members 19 extending above block 10 are formed as handles or finger pieces 19b. Members 19 are connected below block 10 to the ends 20 of tension coil spring 20. A small bar 21 is secured to the central portion of the strip 17 and extends beyond the sides thereof, said bar having a slot 21a therein through which the lower portions of members 19 extend.

25 In operation, when the band or lining such as shown at 22 in Fig. 1 is to be placed on a shoe, a portion of which is shown at 23, it will be laid upon the shoe so that its ends are approximately in the proper position at the ends of the surface 23a of said shoe. As above stated, the bands now used come cut to length, and said bands are often quite distorted. The device will now be taken by the operator and the upper ends 30 19b of the members 19 moved together and the hook portions 19a placed under the flanges 23b of the shoe 23. Members 19 are then released and the device is thus connected to the shoe 23. Strip 17 will engage the band 22 at its end portions or at the ends of arms 15. The central portion of 35 the strip 17 will be slightly spaced from the band. The band will now be accurately adjusted to the shoe laterally, and the operator will turn handle 12, thus moving member 14 downwardly away from block 10 and thus moving the adjacent ends of arms 15 downwardly, causing the outer ends of said arms to move away from each other as they are pressed against the band 22. The pressure of the ends of the strip 17 or the 40 ends of the arms 15 against the band as they move away from each other, gives a stretching movement to the band, and it is pulled down tightly over the surface 23a. The movement of the wheel 12 and screw 11 is continued until the entire surface of the strip 17 comes into engagement with the top of the band 22 as shown in Fig. 1. Band 22 is now stretched and drawn down on the surface 23a and pressed against the same with great force, so that it is in very tight engagement with said surface. The band 22 can 45 now be riveted to the shoe by placing the rivets 24 through the proper holes in the band 22 and the holes made in the flanges 23b of the shoe 23. The band is thus connected to the shoe and is in very tight engagement with the surface thereof. The device can then be released by unscrewing screw 50 11 and moving the portions 19b of members 19 together to release the hook portions 19a. If the shoe is quite long, the device can be moved to two or more places thereon and the band stretched 55 tightly down onto the portions of the shoe.

60 From the above description it is seen that applicant has provided a very simple and yet a very efficient device for stretching the band and pressing it into firm engagement with the shoe. The device is capable of exerting great pressure, 65

and the band is pressed against the shoe so tightly that a very thin article, such as a piece of paper, cannot be drawn from under the band when it is in its pressed condition. The device exerts both a drawing and a pressing effect on the band, 80 so that all irregularities on the band are smoothed out and a perfect fit is had on the shoe. The device can be easily and quickly operated, and the band accurately adjusted on the shoe. The device is quite simple and can be made strong and durable. The same has been amply demonstrated in actual practice and found to be very successful and efficient. 85

90 It will, of course, be understood that various changes may be made in the form, details, proportions and arrangement of the parts, without departing from the scope of applicant's invention, which, generally stated, consists in a device capable of carrying out the objects above set forth, in the novel parts and combinations of parts disclosed and defined in the appended claims. 95

What is claimed is:—

1. In a brake shoe lining assembling tool, means for engaging and holding a brake shoe against 100 pressure, a member movable toward the convex side of said shoe so held, arms pivoted to said member extending at opposite sides thereof and having concave under sides adjacent said brake shoe, a flexible strap extending between and connected to the outer ends of said arms, and means for moving said first mentioned member for applying pressure to said member and arms, for both laterally shifting said outer ends of said arms approximately parallel to the convex surface 105 of said shoe for stretching a brake lining thereon, and causing said strap to hug said lining and press the same against said convex surface of said brake shoe. 110

2. In a brake shoe lining assembling tool, a 115 frame having relatively swinging arms adapted to engage and hold a brake shoe, arms pivoted to said frame and extending outwardly therefrom in opposite directions, said arms extending downwardly and outwardly toward the convex 120 surface of said brake shoe, a strap extending between and having its ends secured to the outer ends of said arms, the outer ends of said arms and strap being adapted for gripping engagement with a lining disposed on the convex surface of 125 said brake shoe, and means for applying pressure upon said frame for both laterally shifting the ends of said arms approximately parallel to the convex surface of said brake shoe for stretching the lining thereon and causing said strap to 130 hug said brake shoe in lining pressing engagement therewith. 135

3. A brake shoe lining assembling tool having in combination, a member tapped to form a nut, a screw passing through said member having a handle thereon, depending arms pivoted to the opposite sides of said member and having hook portions at their lower ends to engage under and hold a brake shoe with the convex surface of 140 said shoe directed towards said member, a second member carried by said screw, arms pivoted to said second member and extending at opposite sides thereof and at right angles to said first mentioned arms, a strap extending between and secured to the ends of said last mentioned arms, said screw being rotatable to apply pressure to said second member for both laterally shifting the ends of said last mentioned arms and strap 145 approximately parallel to the convex side of said 150

brake shoe for stretching a lining thereon and causing said strap to hug said brake shoe in lining pressing engagement therewith.

4. The structure set forth in claim 3, said first 5 mentioned arms having portions extending above their pivots adapted to be engaged to separate the lower ends of said arms.

5. The structure set forth in claim 3, and means extending about said arms above said strap adapted to prevent separation of the lower ends of said arms when engaged with said brake shoe.
